UNITED STATES PATENT OFFICE.

MAX WIELAND, OF AUERBACH, NEAR CHEMNITZ, GERMANY.

CONICAL BOBBIN ARRANGED WITH STEPS.

Application filed July 5, 1927, Serial No. 203,659, and in Germany July 6, 1926.

This invention relates to bobbins upon which is wound thread or yarn, etc., used in the textile industry, and has for its object to provide a conical or bottle shaped 5 bobbin having formed thereon a plurality of sets of annular steps, each set of steps differing in depth and height from the adjacent set, the arrangement of which steps allows the thread to be wound on the bobbin 10 more evenly, prevents the thread from forming beads or beat formations, and avoids the unintentional slipping off of the thread wound on from the bobbin.

Another object of the invention is to provide 15 a conical bobbin having a plurality of sets of annular steps, each set of steps differing in depth and height and disposed with a set of steps having the least depth and height at the largest end of the conical 20 bobbin.

A practical embodiment of my invention is represented in the accompanying drawings, in which—

Fig. 1 represents an elevation of a conical 25 bottle shaped bobbin having my improvement applied thereto;

Fig. 2 represents a similar view of a modified form of bobbin showing the thread and thread guide diagrammatically;

Fig. 3 represents a similar view of the bobbin with the thread and thread guide removed;

Fig. 4 represents another modified form of bobbin, and

Fig. 5 represents an elevation of a conical 35 bobbin.

In Fig. 1 the cylindrical portion of the bobbin is denoted by α , and the conical portion by α' , α'' . A thread guide b (shown in Fig. 2) is located in its extreme position at one end of the bobbin and is moved to guide the thread c as it is wound on the bobbin.

The conical portion α' of the bobbin is provided with a set of annular steps e , each 45 of said steps having substantially the same depth and equally spaced apart. Each of the steps has a different diameter from that of the adjacent step. The conical portion α'' of the bobbin is also provided with a set 50 of annular steps e , each of which steps also has substantially an equal depth and is approximately the same height. The diameter of each step is smaller than the diameter of the adjacent step as it approaches the cylindrical portion α . The set of steps e' are

smaller in depth and height but larger in diameter than the set of steps e .

From the foregoing it will be seen that the conical portion of the bobbin has two sets of steps, each set of steps differing in 60 depth and height, and disposed with the set of steps having the smallest depth and height at the largest end of the conical bobbin.

In the form shown in Fig. 4, the conical 65 bobbin is provided with a set of steps e , a set of steps e^2 having a smaller depth and height than the set of steps e , and a set of steps e' , which set of steps is smaller in depth and height than the set of steps e^2 . 70 In this form, the sets of steps progressively increase in depth and height as they decrease in diameter.

In the form shown in Fig. 5 the set of steps e is developed to the extreme small end 75 of the bobbin, while a set of steps e' is arranged to progressively increase in diameter and diminish in depth and height toward the large end of the bobbin.

While I have shown and described the 80 set of steps having the smallest depth and height disposed at the largest end of the conical bobbin, I also find it advantageous to locate a set of steps having a smaller depth and height at each end of the conical 85 bobbin and a set or sets of steps having a larger depth and height interposed between the set of steps of smaller depth and height.

It has been found in practice that a bobbin formed with sets of steps having a different 90 depth and height wound with thread will hold the body of thread firm and even. Furthermore, by this structure the thread will be wound on the bobbin uniformly, without being caused to pile up and form beads on 95 the end of the bobbin where the thread guide changes its direction.

What I claim is:

1. A bobbin comprising, a conical portion provided with a plurality of sets of annular steps, each set of steps being decreased in depth and increased in diameter.

2. A bobbin comprising a conical portion provided with a plurality of sets of annular steps each set of steps being decreased 105 in depth and height and increased in diameter.

3. A bobbin comprising, a conical portion provided with a plurality of sets of steps, each set of steps having a different depth 110

from the adjacent set of steps, the smallest depth of said sets of steps being disposed at the larger end of the conical portion.

4. A bobbin comprising, a conical portion provided with a plurality of sets of steps, each set of steps having a different depth and height from the adjacent set of steps, the smaller depth and height of said sets of steps being disposed at the larger end of the conical portion.

5. A conical bobbin provided with a plurality of annular steps of different depths

and heights, the smallest of said steps being located at the larger end of the bobbin.

6. A conical bobbin provided with a plurality of annular steps of different depths and heights extending substantially throughout its entire length, the smallest of said steps being located at the larger end of the bobbin.

In testimony that I claim the foregoing as my invention, I have signed my name this 21st day of June, 1922.

MAX WIELAND.
